UNITED STATES PATENT OFFICE.

LEWIS J. MILLER, OF BERGEN, NEW YORK, ASSIGNOR OF ONE-FOURTH TO GEORGE M. NEAL, OF BERGEN, NEW YORK.

SAFETY ATTACHMENT FOR TROLLEY-RAIL SWITCHES.

1,144,371.

Specification of Letters Patent. Patented June 29, 1915.

Application filed November 7, 1914. Serial No. 870,865.

To all whom it may concern:

Be it known that I, LEWIS J. MILLER, a citizen of the United States, residing at Bergen, in the county of Genessee and State 5 of New York, have invented new and useful Improvements in Safety Attachments for Trolley-Rail Switches, of which the following is a specification.

This invention relates to improvements in 10 safety devices for trolley rail switches and has for its primary object the provision of a structure whereby the wheels of a carriage are positively held against running into an open switch.

Another object of the invention is the 15 provision of a structure whereby the free end of the switch is rigidly held against downward movement when sustaining the weight of the carriage.

A further object of the invention is the 20 provision of a structure which will gravitate to operative position simultaneously with the opening of the switch.

A still further object of the invention is 25 the provision of an article which can be cast into its formation and readily delivered from the mold for producing an inexpensive article.

The invention consists in the features of 30 construction, combination, and arrangement of parts, hereinafter fully described and claimed, reference being had to the accompanying drawing, in which:

Figure 1 is a side elevation of a trolley 35 rail switch, showing the safety device in operative position. Fig. 2 is a view showing the safety device supporting one end of the switch. Fig. 3 is a cross section thereof. Fig. 4 is a longitudinal section of Fig. 2 40 showing the safety device in an inoperative position and supporting one end of the switch. Fig. 5 is a longitudinal section of Fig. 1 showing the safety device in an op-

erative position. Fig. 6 is a perspective view of the device.

Referring to the drawing, the numerals 1 and 2 designate the ends of a trolley rail, the space therebetween being bridged by the switch 3.

The numeral 4 designates my safety device which is cast U-shaped in cross section so as to contact with the opposite sides of the rail 2 when pivotally connected as shown at 5. The metal at the juncture of the forward portion of one side 6 of the casting 55 with the forward portion of the side 7 forms a shoulder 8 which is adapted to contact with the end of the rail 2 for limiting the swinging movement of the device from its pivot 5 when gravitating to a position for 60 obstructing passage over the rail ends.

In Fig. 2, I have shown a portion of the device supporting one end of the switch when sustaining the weight of the carriage and when in this position, the flat bottom 65 portion 9 contacts with the flat under surface of the rail end 2, thus the switch end is held against relative movement with relation to the rail end 2.

What is claimed is:

In combination with a pair of fixed rails and a switch rail, of a safety device therefor comprising a casting pivotally connected to one of said fixed rails and adapted to support one end of said switch when in an 75 operative position, said casting being U-shaped in cross section so as to contact with the sides of one of said fixed rails for preventing lateral movement of the casting and to limit the vertical movement of the latter. 80

In testimony whereof I affix my signature in presence of two witnesses.

LEWIS J. MILLER.

Witnesses:

EARL H. PARISH,
EDWARD M. KEARNEY.
